PERCUSSIVE TOOL

Irvin R. Danielson, Burr Ridge, Ill., assignor to Thor Power Tool Company, Aurora, Ill.

Filed Jan. 17, 1972, Ser. No. 218,660

Term of patent 14 years

Int. Cl. D8—05

U.S. Cl. D8—70

FIG. 1 is a front view of a percussive tool showing my new design;

FIG. 2 is a side view;

FIG. 3 is a rear view;

FIGS. 4 and 5 are end views;

FIG. 6 is a front view of another percussive tool embodying my new design; and

FIG. 7 is a side view of the percussive tool shown in FIG. 6.

I claim:

The ornamental design for a percussive tool, as shown.
